FOLDING CABINET BED

Joseph R. Thomas, Chicago, Ill.

Application January 20, 1939, Serial No. 251,922

6 Claims. (Cl. 5—149)

This invention relates in general to a sectional folding bed enclosed in a cabinet, desk, chest of drawers, table, or other article of furniture and movable outwardly and unfolding to provide a bed of normal dimensions and including a mattress of material thickness for providing a sleeping surface.

In cabinet folding beds of this type it has heretofore been necessary either to provide a cabinet of objectionable height, too high for a table or stand, to make the top hinged or otherwise movable, or to provide a cabinet or container of such unusual dimensions that it is objectionable as an article of furniture. The usual table or desk should not have a top surface much higher than 31 or 32 inches from the floor or it will be objectionably high, and to provide a stand or container in which the top must be raised or removed, or the folding structure swung out at the back is further objectionable as an article of furniture.

The present invention overcomes these objections by providing a sectional folding bed bottom which is collapsed in a particularly compact relation so that a full length bed may be included in a cabinet which is not objectionably high, with a fixed top, so that the folding sections are pulled outwardly from below the top either by means of doors which are opened prior to unfolding or by false doors which are opened and unfolded with the bed structure itself.

An important object of the invention is therefore in the provision of a sectional folding bed structure in which the method of folding is such that a full length bed can be incorporated as a part of an enclosing structure which is neither too high nor too ungainly as to form a pleasing and desirable article of furniture which may be made up to resemble a table, desk, chest of drawers or other article of furniture.

A further object of the invention is in the provision of a cabinet folding bed structure in which the folding parts are so related that they may be included below a fixed top of suitable height and compactly arranged therein to fold and unfold automatically as the sections are inserted and pulled out from below the fixed top.

A still further object of the invention is in the provision of a compactly folding bed structure which may be incorporated as an article of furniture below a fixed top or may be inset in a wall niche or recess of minimum dimensions and easily folded or unfolded therefrom.

A further object of the invention is in the provision of improved means for supporting the

cabinet forming a part of the bed structure in the folding and collapsing movement of the bed sections in moving them into and out of the cabinet.

5 A still further object of the invention is in the provision of a folding bed structure in which the folding of the sections is so compact that a mattress of usual thickness can be included therewith and the whole incorporated as a part of a pleasing article of furniture substantially the height of the ordinary table or desk.

Other and further objects of the invention will appear hereinafter, the accompanying drawings illustrating preferred embodiments of the invention, in which—

Fig. 1 is a perspective of a cabinet in closed condition in which the folding bed structure is enclosed;

20 Fig. 2 is a view partly in section of the cabinet showing a bed bottom therein in folded position;

Fig. 3 is a side elevation of the folding bed structure in partially open position;

Fig. 4 is a partial plan view and

25 Fig. 5 is a side elevation showing the folding bed structure in open or extended bed position;

Fig. 6 is a perspective of a modified cabinet for desk or table purposes;

Fig. 7 is a sectional view of the cabinet shown 30 in Fig. 6 and a side elevation of the bed structure folded within the cabinet;

Fig. 8 is a side view showing the bed of Fig. 7 in extended or bed position;

Fig. 9 is a view showing the bed structure of 35 Figs. 7 and 8 in intermediate or partially folded position; and

Fig. 10 is a detail view showing the connection of the rear bed section to the cabinet shown in Figs. 7 to 9.

40 While this invention is described as applied to a plain cabinet having a top 20 fixed in position with respect to sides 21, a rigid back 22 and front middle opening doors 23 hinged at the sides, it should be understood that the cabinet itself may be made the subject of various designs, the front may be made to represent drawers as in Fig. 11, and in some forms to resemble a conventional table or a desk as in Fig. 6, or the folding bed structure may be inserted in a wall opening and covered with drawers or a drawer front.

45 In the form shown in Figs. 1 to 5 a folding bed structure comprising a plurality of sections is mounted at each inner side of the cabinet by means of a pair of levers 24 and 25 pivoted to a 50 spacing and attachment bar 26 which is secured

at a predetermined position by suitable fastening devices 27. One of the levers 24 has a pivot 28 at its end connecting it to one end of the bar 26 and the other lever 25 has a pivot 29 connecting it near one end at the other end of the bar 26. The other extremities of these levers are connected at spaced distances apart to an angle bar 30 by pivots 31 and 32, the angle bars being connected at opposite sides of the cabinet to a rear section 33 of the folding bed bottom, thereby constituting the direct connection and support for attaching the folding bed bottom in the cabinet and for holding it both in collapsed and extended positions at the proper height, location and position with respect to the cabinet.

Connected to the rear bed section 33 are front and intermediate sections 34 and 35 directly hinged together by means of a plate 36 at each side joining their proximate ends. At the other end of the intermediate section is a double hinged connection consisting of a link 37 having a pivot 38 at the end of the section 35 and a lever 39 bent at one end somewhat in the form of a bell-crank having a pivot 40 at a slight distance from the end of the section 35. The other ends of these members are connected by pivots 41 and 42 to a cross bar 43 fixed at the adjacent end of the rear section 33 by means of a brace 44 and extending to opposite sides above and below the end of the rear section 33 so that the pivots 41 and 42 are at opposite sides, above and below its connection with the bar 43 respectively.

To support the outer and intermediate sections a leg 45 is pivoted intermediate the ends of the front section 34 and a leg 47 is pivoted adjacent the rear end of the intermediate section 35. These legs are folded and unfolded in accordance with the collapsing or extension movement of the bed sections by means of a link 48 connected by a pivot 49 to the angle portion of the bell-crank 39 and connected by a pivot 50 at its other end to the plate 36. Extending from the upper end of the leg 47 is a link 51 connected at one end to the leg and at the other end to the link 48. Connected to the leg 45 adjacent its upper end is a link 52 having its other end connected by a pivot 53 near the adjacent end of the link 48.

In their folded positions the legs 45 and 47 lie against or in close relation to their corresponding sections 34 and 35 and they are moved to supporting position when the bed sections are unfolded by the movement of the controlling link 48 as it is moved by the bell-crank lever 39, which is therefore termed the coordinating linkage for automatically controlling the folding and unfolding movement of the bed bottom as it is collapsed or extended. In the partially folded position as shown in Fig. 3 the legs are extended substantially to their supporting position and a further outward movement will cause them to be locked in position because of the straight line connection between the links 48 and 52 so that the extended bed will be locked against collapsing, and when the outer section is manually raised for storing it within the cabinet any further inward movement will cause the legs to be gradually folded by the coordinating linkage against their respective sections.

Side bars 43 are connected at their lower ends by a cross bar 54 which constitutes a spacing strut for holding this portion of the frame distended laterally against the tension of the mattress supporting fabric 55 and the helical springs 56 at the sides thereof which tend to hold the fabric tight within the frame formed by the bed sec-

tions. Cross braces 57 are also connected be-

tween the legs 45 and 46 on opposite sides of the frame for strengthening and holding the bed frame in distended position.

When the folding bed is being extended or returned to the cabinet there is a tendency to overturn the cabinet forwardly due to the weight of the bed structure. To partially counteract and to stabilize the cabinet a stabilizing lever 60 has a pivot 61 near one end connecting it for rotation to the side of the cabinet and also for connecting it by means of a spacing link 62 with the mounting bar 26 at its side of the cabinet to which it is connected by the pivot 29. Extending from the short or lower end of the bed mounting lever 25 is a link 63 having a pivot 64 at one end for connecting it with the end of the lever 25 and a pivot 65 at the other end for connecting it with the stabilizing lever 60. At its outer or free end this stabilizing lever is provided with a contact piece 66 preferably a small rubber button, and at the opposite end is a spring 67 connected at one end to the lever and at its other end to a fixed eye or support 68 which tends to pull the stabilizing lever downward from its raised position as shown in Fig. 2 to its applied position as shown in Fig. 3, into which it is positively operated and held by the link 63 until the middle and outer sections are moved inwardly to such a point where there is no longer any danger of overturning the cabinet, at which time the stabilizing lever is automatically turned upwardly about its pivot 61 and the contact button is engaged by one of the doors 23 as it is closed, pressing the lever inwardly against the tension of the spring 67. Thus the door tends to complete the folding action and positioning of the bed frame within the cabinet and the spring 67 tends to tension the door in its closed position.

To partially counterbalance and assist the inward and outward movement of the bed frame a coil spring 69 is connected at one end to a support 70 fixed in the cabinet and at the other end to an arm or projection 71 near the end of the lever 24 pivoted in the frame.

In moving the folding bed in and out of the cabinet it is supported by rollers or castors 72 at the lower ends of the middle legs 47 and as the outer legs 45 are raised or lowered with the outer sections 34 in withdrawing and collapsing the bed frame sections, they are moved easily in both directions as the inner section is substantially balanced on the arms 24 and 25 and counterbalanced by the spring 69.

In this method of folding the innermost and outermost sections 33 and 34 are foldable together with their bed surfaces adjacent but separated by a mattress 73 of suitable weight and thickness, usually tied or otherwise attached to the bed fabric or the folding bed sections so that it will fold readily therewith. The sections between the inner and outer bed sections are disposed at the bottom, the middle section 35 being at the bottom of the cabinet and connected to the inner bed section 33 by the double links 37, 39 so that the structure when folded is substantially L-shaped with a space 74 at the back of the cabinet between the upright rear section 33 and the rear of the cabinet into which pillows and bed clothes may be tucked or folded when not in use. A material advantage of this method of folding is that by connecting the sections to collapse in a substantially L-shaped fold the cabinet itself may be made of more pleasing proportions both as to height and to depth, so that a pleasing article of furniture may be pro-

vided, not too high for a table or desk, and not too wide or deep as to be clumsy or ungainly in appearance.

At the bottom of the cabinet are suitable rests or gliders 75 preferably located at the corners of the cabinet and also on the doors 23 particularly at the outer ends thereof and upon the outer legs 45. At the bottom of the cabinet is a panel 76 which may cover the entire bottom, adding strength and rigidity to the cabinet. The rollers or casters 72 may engage beveled front edges at the sides, or may roll freely into and out of side recesses at the sides of the panel in folding and unfolding.

In mounting the bed structure within the cabinet the connected bed sections may be fabricated as a unit separately from the cabinet supporting means comprising the spacing bars 26 and 62, the levers and arms connected therewith, and the angle bar 30. The various supporting links might be connected directly to the inner walls of the cabinet but in practice it is found preferable to mount them upon the bars 26 and 62 and to connect the bars by separate fastening bolts 27 or the pivots which attach the levers to the bars 26 and 62 for the purpose of more accurately locating the pivot points of the supporting levers and links and also for holding them more accurately in position. The connected bed sections may then be separately attached to the lower or horizontal webs of the angle bars 30 by bolts, rivets or other fastening means 77 as shown more clearly in Fig. 4. This also provides for a variation in width of the cabinets without requiring any variation in width of the bed structure or of the supporting means therefor in the cabinet.

The linkage structure for operating the outer legs 45 also acts in connection with the co-ordinating bars 48 as a double lock, to hold the sections within the cabinet in folded position as shown in Fig. 2, and to hold the legs 45 against collapsing in the extended position of the bed. To unlock the sections for unfolding the upper cross bar 57 connecting the legs 45 may be grasped and pulled outwardly, which moves the pivots 53 inwardly out of locking line with the pivots 50 and allows the natural unfolding and drawing out of the sections to their extended position as shown in Fig. 5 from which position the outer section must be raised, breaking the locking connection as shown in Fig. 3 before the bed sections can be folded and collapsed within the cabinet as shown in Fig. 2.

To limit the forward movement of the bed sections and to assist in supporting the rear section in unfolded position, the mounting or angle bar 30 at each side is provided with a fixed stop 78 adjacent the pivot 31 of lever 24 which is engaged thereby in the unfolding movement of the bed sections and together with the lever 25 serves to hold the rear bed section 33 at the correct elevation and against movement in either direction until it is properly unfolded. A spring 79 is also connected at one end to each side of the intermediate section 35, the other end of the spring being connected to a cross brace 51 on the leg 47 so that the spring tends to oppose the closing of the leg and to assist in drawing it to open position. This is to insure the proper positioning of the legs 47 when the bed bottom is extended to form a bed.

In the form shown in Figs. 6 to 10, inclusive, the folding bed structure is substantially the same as shown in the preceding figures, it folds

substantially in the same L-shape but is inverted in a cabinet 80 having a fixed or rigid top 81 and the inversion of the bed structure provides a leg space 82 at the front of the cabinet so that it is adapted for use as a desk or table when the bed structure is collapsed within it. The inversion of the bed structure also alters and simplifies the bed supporting structure which comprises a mounting bar 83 mounted at each inner side of the cabinet by fastening means 84 and having links 85 and 86 positioned, spaced apart and each pivoted at one end to the mounting bar 83 and connected by pivots 87 and 88 to the rear bed section for swingingly mounting it in the cabinet. The sectional connections and folding features of the bed structure are the same as previously described with the exception that a cross bar 89 is substituted for the cross bar 43 and extends further below the bed section 33 to provide a support for a front board 90 which is carried thereby from a position just below the top as shown in Fig. 6, to a position below the folded sections as shown in Fig. 8. Also projecting from the lower side of the rear section 33 is a front panel 91 secured to and spaced from the side frames of the rear section 33 by brackets 92 and held fixedly in connection therewith so that the panel 91 and front board 90 thus substantially enclose and hide the bed structure within the cabinet when it is folded, giving the cabinet a finished and different appearance resembling either a desk, table or other structure, depending upon the design and construction thereof.

Pivoted at the ends of the front board 90 or to a cross bar 54 connected to the lower ends of opposite bars 89 by means of pivots 93 are short legs or supports 94 each having a rubber tip or button 95 at its lower end movable either manually or by gravity when the bed structure is unfolded, and adapted to engage the floor below the end bars 89 and to form a support for this portion of the bed when it is in extended or unfolded position. When the bed structure is raised and collapsed within the cabinet these supports 94 are turned inwardly by hand below the front board 90 and will not be visible when the structure is completely folded. In practice these supports 94 are turned outwardly before the bed structure is pulled out so that they will be ready for engagement with the floor as it is extended.

In this form of the invention no stabilizer is shown as the mounting of the folding bed is such that the first action is to turn it downwardly from within the cabinet as shown in Fig. 7, upon its mounting links 85 and 86, until the supports 94 engage the floor as shown in Fig. 9, and from this position the sections are unfolded to the extended position and are returned from the extended position in folding the bed so that the next movement is to invert it within the cabinet and below the fixed top thereof.

Thus the bed sections are compactly foldable within a cabinet having a fixed top at a low level which adapts the cabinet structure for use as a usual or commonly employed article of furniture and of such dimensions that it is not objectionable either as to depth or height, and when the bed is incorporated in a movable cabinet stabilizing means are provided for preventing the cabinet from overturning in the folding and unfolding operations of the bed sections so that if desired other articles may remain on top of the cabinet without the necessity of re-

moving them for the folding and unfolding operations of the bed structure. This construction also is particularly adapted for use in a wall niche or recess of minimum dimensions so that it may be used as a regular or emergency bed and concealed when not in use in a door or drawer structure of minimum height which appears as a part of a built in cabinet or fixture.

I claim:

1. In a folding bed, a plurality of bed sections, a pair of which are hinged directly together, and a mounting section connected to one of the other sections by a double link hinge so that all of the sections are in alignment when they are extended, the mounting section having a cross bar extending above and below the section to which the extremities of the mounting links at each end are connected, and the cross bars on opposite sides being connected by a cross piece below the level of the bed frames when extended, and means for supporting the said mounting section to swing from an upright vertical position to a horizontal position in alignment with the other sections when they are extended.

2. The combination with a cabinet structure having a fixed top and a front opening, a folding bed structure composed of connected sections, the rearmost end section having pivoted links for mounting it in a vertical position within the cabinet and to swing it therefrom to a horizontal position extending from the cabinet, a stop fixed on the rearmost section for engaging one of the mounting links at each side of the cabinet for limiting the movement of the bed sections and for holding the rear section in proper alignment, the other sections being connected by a direct connection and by a double hinging link connection adapting the sections to fold together in a compact double L shape, one L nested within the other, and both within the cabinet.

3. The combination with a cabinet comprising a front opening, a folding bed comprising a plurality of connected sections foldable within the cabinet and movable therefrom, means for mounting one of the end sections upon a pair of pivoted links at each side for movement from a vertical position within the cabinet to a horizontal position extending from the cabinet, and a stabilizer connected to and operated by one of the links and pivoted to the side wall near the front and bottom thereof within the cabinet comprising an arm movable into engagement with the floor at the front of the cabinet

as the sections are moved into alignment and remaining in such engagement for a portion of the time that they are being returned into the cabinet.

4. The combination with a cabinet or recess of fixed height, depth and front opening, of a folding bed structure to fold compactly therein into a substantially double L-shaped position, one L being seated in but spaced from the other, said structure being composed of a plurality of sections connected directly together and by a double link connection between two of the sections, coordinating link means connecting the sections at each side thereof to limit the folding from a position in alignment in front of the cabinet to the double L position within the cabinet, means for mounting the sections to swing within the cabinet or recess below the fixed top thereof, said means comprising a pair of links connected to the rearmost section, and a stop on the rearmost section located rearwardly of the connection of the links thereto for engaging the upper edge of one of the links at each side for limiting the unfolding movement of the sections and to provide a support for the inner end of the said rearmost section.

5. A structure in accordance with claim 4 in which legs for supporting the outer sections are each pivoted at its upper end to one of the sections and pivoted adjacent its upper end to the said coordinating linkage so that the pivot points thereof are movable past a center point between them and the legs form therewith a lock in both the folded and extended position which must be manually disengaged by moving the leg connectors free from a locking position before the sections can be unfolded from a cabinet or recess or released from extended position.

6. A cabinet structure with a front opening, in combination with a sectional folding bed having mounting links connecting the rearmost section to the inner sides of the cabinet, a stabilizing arm pivoted to the side wall at the front within the cabinet and having a member pivoted thereto and to one of said links and being quickly movable thereby in the folding and unfolding action of the bed sections so that the arm engages the floor in front of the cabinet soon after the unfolding movement of the bed structure commences and remains in such engagement until the bed structure when being collapsed is nearly returned within the cabinet, to prevent the forward overturning of the cabinet.

JOSEPH R. THOMAS.
